UNITED STATES PATENT OFFICE.

GUST WILLIAM PETERSON, OF LONG BEACH, CALIFORNIA.

LATHERING DEVICE.

Application filed September 23, 1924. Serial No. 739,430.

To all whom it may concern:

Be it known that I, GUST W. PETERSON, a citizen of the United States, and a resident of Long Beach, in the county of Los Angeles and State of California, have invented certain new and useful Improvements in Lathering Devices, of which the following is a specification.

My present invention relates generally to 10 shaving accessories and more particularly to lathering devices, my object being the provision of a simple inexpensive lather spreading and beard softening device to take the place of the usual unsanitary, more expensive and less satisfactory brushes.

While susceptible of various forms, my invention contemplates in its most simple embodiment a section of material such as 20 sponge rubber fixed to a backing or supporting plate, the plate having provision for engagement of a handle and the rubber spreading element having a central cavity or opening for the reception of the soap to be subsequently spread in the form of lather 25 prior to shaving. Preferably the section of sponge rubber is approximately semispherical in form, its nature and shape rendering the same peculiarly effective as a beard softener during the lathering operation.

30 The invention is also well adapted to other forms, for instance as a fountain applicator in connection with shaving cream holders, and I have fully shown the preferred form in the accompanying drawing 35 wherein,

Figure 1 is a perspective view showing the invention,

Figure 2 is a central vertical section through the upper portion thereof, and

40 Figure 3 is a horizontal section taken on line 3—3 of Figure 2.

Referring now to these figures I have shown my invention in the form of a fountain applicator for a shaving cream holder 45 in the usual flexible tubular shape as indicated at 10. The spreading element 11 is an approximately semispherical section of sponge rubber having an axial feed opening 12 therethrough and permanently fixed in 50 any suitable manner upon a flat circular supporting plate 13 provided with a central

opening 14 to register with the feed opening 12.

The plate 13 preferably has an annular flange 15 which in this instance is crimped 55 around the annular edges of a pair of valve holding discs 16 and 17 having central openings and having their central portions spaced apart to receive therebetween a flat shutter valve 18 shiftable to cover or uncover the opening of disc 17 as will be plainly seen by a comparison of the full and dotted lines of Figure 3.

At one end the valve or shutter 18 has an angular rounded projection 19 movably interfitting an opening in the disc 17 and adjacent to its opposite end this valve or shutter has a projection 20 slidably mounted in an arcuate slot 21 in disc 17 and projecting through said slot so that it may be conveniently reached by the operator for shifting the valve to closed or open positions.

Around its central opening, disc 17 is fixed to one end of a tube 22 whose opposite end is adapted to telescope the discharge 75 neck 23 of the container 10. Thus, with the valve 18 shifted to uncover the opening of disc 17, the cream within container 10, or a proper supply thereof, may be readily forced out through the tube 22, disc openings and the plate opening 14 into the feed opening 12 of the spreader. Then by shifting the valve to cover the opening of disc 17 further feed will be stopped, and thus in the lather spreading and beard softening 80 operation, the container 10 may be used as a handle, attached as it is to the tube 22.

Other forms of construction may be adopted, and though I have shown and described the preferred form it is to be understood that I include as a part of my invention all such modifications to which it may be conveniently applied and which came within the terms of the claims.

I claim:

1. A lather spreader and beard softener including an applicator of soft compressible material having an axial opening, a supporting plate on which said applicator is fixed, a pair of discs held by said plate, one of which discs has an axially projecting tube, and a valve member shiftable between

said discs, the discs and said plate having register openings communicating between the said tube and the axial opening of the applicator and forming therewith a feed channel for which said valve acts as a cut-off.

2. A lather spreader and beard softened including an axially apertured applicator formed of sponge rubber, a support therefor

including a projecting tube and spaced 10 apart members apertured to communicate between the tube and the axial aperture of said applicator and thus form a feed channel, and a manually shiftable valve supported by and between said members for closing and opening said channel.

GUST WILLIAM PETERSON.
